UNITED STATES PATENT OFFICE.

WILLIAM M. CHATARD, OF BALTIMORE, MARYLAND.

MATCH-BOX HOLDER.

No. 893,225.

Specification of Letters Patent.

Patented July 14, 1908.

Application filed November 19, 1906. Serial No. 343,998.

To all whom it may concern:

Be it known that I, WILLIAM M. CHATARD, of Baltimore, Maryland, have invented certain new and useful Improvements in Match-5 Box Holders, of which the following is a specification.

The invention was devised particularly for the usual safety match boxes and its object is to enable the boxes to be held in a convenient manner and place readily accessible in the dark and to accomplish this by a holder that may be very cheaply and economically manufactured and very easily used.

15 The drawings show several forms of my holder.

Figures 1, 2, and 3 are perspective view of the preferred form, longitudinal section thereof, and a view showing the manner of putting 20 on and taking off from the box. Fig. 4 shows a modification.

The box, consisting of cover *b* and tray *c*, is held in a partly open position and preferably suspended by a chain *d* having a ring *f* 25 which may be slipped over the usual gas burner, allowing the holder and box to hang therefrom in convenient position for finding even in the dark.

In Figs. 1, 2, and 3 the holder is of sheet 30 material, as brass or nickel plate, and provides a back piece *g* having at the upper end a perforated fold forming an ear *h* for attaching the chain *d*, and a bent or folded portion at *j* which clasps and holds the edge of the 35 tray *c*, as shown. The manner of putting the holder on is shown in Fig. 3. The lower end has a similar bent or folded clasp *k* which clasps the lower edge of the cover *b*, as seen. When this clasp *k* has been put in place and 40 the cover drawn down into it, as in Figs. 1 and 2, the box is held firmly and cannot open any further. In this form of the device the back *g* lies outside the cover *b*. The central position of the ear *H* causes, as seen in Fig. 2, 45 the box to hang in a straight or vertical position instead of tilting forward, as would occur if hung from any point in the plane of the bottom of the tray.

In the modification shown in Fig. 4, the 50 back lies within the cover and has a rest formed by a bend *m* for one end of the tray, another bend and clasp *j* holding the upper end of the tray, and a bend or clasp *q* for the lower edge of the cover.

55 It will be seen that all the forms shown in-

clude a strip comprising a back-piece with the upper portion bent forward and then upwards and perforated to receive the hanger or chain *d*. Also, that all the forms shown have clasps or stops limiting the downward opening movement of the box cover.

The holder presents a very finished and neat appearance owing to its construction, and avoids the necessity of tongues and projections punched out from the sheet metal 65 and the unsightly appearance due thereto.

There are other forms, of course, in which the invention may be embodied and I do not attempt to enumerate or develop these.

What I claim is:

1. In a holder for tray-and-cover match boxes, a bent strip comprising a back-piece having at its upper portion a forward bend adapted to engage the upper end of the tray and limit its upward motion, an upwardly- 70 bent portion projecting upwards from the end of the tray at substantially the center of the tray end for attachment to a means of suspension whereby the box will hang in a substantially straight and vertical position 75 without other support and having a folded portion or bend for clasping the tray edge and at its lower end having a bent-over clasp for embracing the lower edge of a partly opened cover, and an intermediate bent rest 80 for the lower end of the tray.

2. In a holder for tray-and-cover match boxes, a bent strip comprising a back-piece bent at its upper end and having a perforated fold forming an ear and a folded portion for clasping the tray edge when in use, 90 and bent at its lower end forming a clasp for the edge of the box cover.

3. In a holder for tray-and-cover match boxes, a bent strip comprising a back-piece 95 bent at its upper end and having a perforated fold forming an ear and a folded portion for clasping the tray edge when in use, and bent at its lower end forming a clasp for the edge of the box cover and having an intermediate bent portion forming a seat for the lower end of the tray.

In testimony whereof I have signed this specification in the presence of two subscribing witnesses.

WILLIAM M. CHATARD.
